UNITED STATES PATENT OFFICE.

WINTHROP L. JACOBS, OF EAST ORANGE, NEW JERSEY, ASSIGNOR TO THE
LOWELL MANUFACTURING COMPANY, OF MASSACHUSETTS.

DESIGN FOR CARPET.

SPECIFICATION forming part of Design No. 24,221, dated April 16, 1895.

Application filed March 14, 1895. Serial No. 541,820. Term of patent 3½ years.

To all whom it may concern:

Be it known that I, WINTHROP L. JACOBS, a citizen of the United States, and a resident of East Orange, in the county of Essex, State of New Jersey, have invented a new and original Design for Carpets, of which the following is a specification.

The accompanying drawing is a face view of a portion of a carpet and border embodying my invention.

The body A is characterized by a series of separate leaf and flower forms having interspersed among them smaller leaf and flower forms.

15 The border B is characterized by a series of flower and leaf forms with smaller interspersed flower and leaf forms along the inner portion. Along the outer portion is a series of figures distinguished by outward spreading

curved lines. Between the inner and outer portions are a series of small ornamental figures distinguished principally by curved lines.

What I claim as my design, and desire to secure by Letters Patent, is—

1. In a design for a carpet, the body A substantially as shown and described.
2. In a design for a border, the border B substantially as shown and described.
3. The design for a carpet, comprising the body A and border B, substantially as shown and described.

In testimony whereof I have signed my name to this specification in the presence of two subscribing witnesses.

W. L. JACOBS.
